UNITED STATES PATENT OFFICE.

HENRY S. HALE, OF PHILADELPHIA, PENNSYLVANIA.

DESIGN FOR AN END FRAME FOR CAR-SEATS.

SPECIFICATION forming part of Design No. 15,053, dated June 10 1884.

Application filed February 14 1884. Term of patent 14 years

To all whom it may concern:

Be it known that I, HENRY S. HALE, a citizen of the United States, residing at Philadelphia, in the county of Philadelphia and

5 State of Pennsylvania, have invented a certain new and useful Design for an End Frame for Car-Seats, of which the following is a specification, reference being had therein to the accompanying drawings.

10 Figure 1 is a front elevation of the end frame of a car-seat containing my design. Fig. 2 is an end elevation showing a modification. Fig. 3 is a similar view showing another modification. Fig. 4 is an edge view of Fig. 1.

15 My invention has for its object the production of a new and original design for the end frames of car-seats; and it consists of a series 45 of ornamental panels arranged around a common center and within the bounding lines of 50 a seat-frame of the ordinary pattern.

20 In the accompanying drawings, A A are the vertical ribs or grooves; B C D are horizontal ribs or grooves, and E a panel having its 55 face ornamented by curved lines which describe various figures. The space between the ribs or grooves C D is divided into four approximately equal parts by a horizontal crossing rib or groove, F, and a vertical crossing rib or groove, G, which intersects the rib 60 or groove F at about a right angle.

25 H H are ornamental panels filling the four spaces which are surrounded or bounded by the ribs or grooves A C D F G. These panels 65 are ornamented by the addition of various figures described by curved lines.

30 In Fig. 2 the design is somewhat modified by the forking or branching of the central parts of the ribs or grooves F G. The small

40 panel thus inclosed is shown blank, but will ordinarily contain a monogram or other suitable characters, which, however, form no part of the design.

45 In Fig. 3 I have shown another end frame containing my new design, which frame differs from that in Fig. 2 by reason of the presence 50 of an ornamental strip or panel, K, extending the entire width of the frame below the panels H H, and in this figure I have also shown the legs L L, which are customarily used to support the end of the seat, but 55 which form no part of the design.

The ornamental figures within the borders 60 of the panels H may be raised or sunken, and when the latter they may extend entirely through the panel without varying the design; 55 or the outlines of the figures may be modified to some extent without materially changing the appearance of the panels.

What I claim is—

A design for an end frame of a car-seat, having 65 four substantially rectangular panels, each bounded in part by one of the outer vertical sides of the frame, in part by dividing ribs or grooves crossing the frame from side to side between adjacent panels, and in part by 70 dividing ribs or grooves crossing the frame from the upper edges of the panels to their lower edges and between adjacent panels, substantially as set forth.

In testimony whereof I affix my signature in 75 presence of two witnesses.

HENRY S. HALE.

Witnesses:

JAS. S. BREEN,
J. WARREN HALE.
